(57) CLAIM

The ornamental design for a laundry bag, as shown and described.

DESCRIPTION

FIG. 1 is a first perspective view of a laundry bag showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the laundry bag thereof;

FIG. 10 is an enlarged view of the selected portion 10 in FIG. 1; and,

FIG. 11 is a perspective view of another state of the laundry bag thereof.

The broken lines shown in the drawings depict portions of the laundry bag that form no part of the claimed design. The dash-dot lines illustrate the boundary of the enlarged views and form no part of the claimed design.
